NEUTRALIZING SYSTEM.

Application filed December 22, 1925. Serial No. 76,981.

This invention relates to radio receiving and amplifying systems and particularly to an arrangement for controlling oscillations in systems which employ a plurality of electron emission tubes coupled together in cascade. In such systems there is always a certain amount of energy exchange or feed-back from the output to the input circuit of the respective tubes caused by internal tube 5 capacitance and magnetic interlinkage between the coupling devices, thus causing objectionable local oscillations or howling.

In the past it has been proposed to neutralize this feed-back coupling by impressing a potential upon the grid which is equal and opposed to the potential imposed by the objectionable feed-back, thus cancelling its effect upon the circuit. Another arrangement secures neutralization by a reverse feed-back of an amount of energy which is equal and opposed to the undesired feed-back. In both of these systems it is impossible as a practical matter to secure perfect neutralization over a substantial frequency range. Theoretical computations are upset by magnetic interlinkage between the inductive transformers employed to couple together the tubes and because of capacity effects between the conductors. As a result such a 20 system may be neutralized for one frequency but will oscillate locally when tuned to another frequency.

It is an object of this invention to devise an electron emission tube system in which 35 neutralization of undesired feed-back energy is secured for the entire frequency range for which the system is adapted.

It is a further object of this invention to secure neutralization of undesired feed-back 40 energy in a system employing an electron emission tube having an input circuit and an output circuit inductively coupled to another circuit, by means including an inductance which is not inductively coupled to the magnetic field of said inductive coupling.

It is a further object of this invention to secure neutralization of undesired feed-back energy in a system employing an electron emission tube having input and output circuits each inductively coupled to other circuits, by means including an inductance 50 which is not influenced by the magnetic field of either of said inductive couplings.

It is a further object of this invention to 55 induce a potential upon the grid of an elec-

tron emission tube to neutralize undesired energy feed-back between the output and the input circuits of the tube by the use of a transformer having a primary inductance electrically associated with the output circuit and a 60 secondary coil electrically associated with the input circuit.

It is a further object of this invention to devise a novel method of neutralizing to prevent local oscillations in an electron emission tube system.

Further objects of the invention will appear from the following description in which the preferred embodiment of the invention has been set forth in detail, it being understood that the invention is only to be limited as defined by the appended claims.

The single figure of the drawings is a circuit diagram illustrating the system of this invention.

The system has been shown as applied to a plurality of electron emission tubes 10 and 11 which in the particular instance are adapted to amplify electrical energy of radio frequency. The tube 10 is provided with an 80 input circuit 12 and an output circuit 13 while the tube 11 is provided correspondingly with an input circuit 14 and an output circuit 15. Output and input circuits 13 and 14 are suitably coupled together by a device 85 later to be described, while the input circuit 12 for the tube 10 is suitably coupled to a source of signal energy of radio frequency. Thus, a suitable absorption circuit such as a radio antenna 16 and ground 17 may be coupled to the input circuit 12 by means of an antenna inductance 18 which is in inductive relation to the secondary inductance 19 in the input circuit 12. A variable condenser 20 is shunted across the secondary 19 so that 90 the input circuit 12 may be selectively tuned over a range of radio frequencies. The tubes 10 and 11 are preferably of the usual type having an electron emission element 22, grid or control electrode 23 and plate or anode 24.

The electron emission element is connected in common to the input and output circuits while the grid 23 and plate 24 are connected respectively in the input and output circuits. The electron emission elements 105 or filaments 22 are energized from a suitable source of energy such as an "A" battery 26, while the respective output circuits of the tubes 10 and 11 are energized from a suitable source such as a "B" battery 27.

The circuits 13 and 14 are electrically coupled together by a suitable transformer 28. Superior results have been obtained by employing a transformer of the auto-transformer type in which a single coil 29 serves as both the primary and the secondary. Thus the entire coil 29 is tuned in resonance with the frequency of the received energy by suitable means such as variable condenser 5 10 15 20 25 30 35 40 45 50 55 60 65

30, while one section 31 of the coil serves as a primary. The intermediate tap 32 which divides the coil 29 into two sections is electrically connected to both of the electron emission elements 22 while the other terminal of the section 31 is electrically connected to the plate 24 of the tube 10 by means of the conductor 35 having a stopping condenser 33 in series with the same. The entire system is preferably shielded by means of 20 a metallic shield 34 which is provided with a partition 36 for minimizing magnetic interleakage between the transformer 28 and the inductance coils 18 and 19. This shield is preferably grounded to the common filament conductor 38 as at 37.

With the arrangement shown the electron emission tubes will have a tendency to oscillate locally due to energy being fed back from the output to the input circuits. This 30 35 40 45 50 55 60 65

feeding back of energy is due principally to the capacitative coupling introduced by the grid 23 and plate 24. It may also be caused in part by capacity effects between the conductors in the input and output circuits or by a small amount of magnetic coupling between the transformer 28 and the inductance 19 in the input circuit 12. To prevent this feed-back energy from causing the tubes to oscillate locally it is necessary to impress a potential upon the grid which is equal and opposite to the potential induced by the undesired feed-back so as to neutralize the same. The applicant has employed an auxiliary inductance coil for this purpose, but this coil is not magnetically coupled to either the coupling transformer 28 or the inductance in the input circuit. Thus there is provided an inductance coil 40 having its one end connected electrically with the filament 22, as 40 45 50 55 60 65

by means of the common filament conductor 38, and has its other end electrically connected to the grid 23 by means of the conductor 41 in series with a small variable condenser 42. For inducing a potential across the coil 40 it is preferable to employ a separate primary coil 43 having its one end electrically connected with the positive terminal of the "B" battery 27 as by means of the conductor 44 and having its other end electrically connected with the plate conductor 45. In the particular system illustrated, the primary coil 43 serves both as a direct current path for the "B" battery 27 and as a means for inducing a potential across the coil 40. 65

The size of the coils 40 and 43 and the de-

gree of coupling between them may vary to suit different operating conditions. However, it has been found preferable to construct these coils so that the resonance period of the coil 43 when coupled to coil 40 70 75

will be below the minimum wave length for which the system is adapted. The neutralizing arrangement for tube 11 need not be described in detail as it is identical with the arrangement shown for tube 10.

In operation condensers 20 and 30 are varied until the system is in resonance with incoming energy. The reactance of coil 43 will cause a large proportion of the amplified radio frequency energy in the output circuit 80 85 90 95 100 105 110 115 120

13 to be transferred to the input circuit 14 of the tube 11 through the coupling transformer 28. However, a certain proportion of the high frequency energy is by-passed by the coil 43 and a potential is thereby induced across the coil 40. The polarity of this potential is reversed by means of the condenser 42 and impressed upon the grid 23 by means of the conductor 41 to neutralize the disturbing potential placed upon the grid 23 because of the feed-back between the output circuit 13 and the input circuit 12. When the system is tuned in resonance with a higher frequency the feed-back of energy between the grid 23 and plate 24 is also increased accordingly, as the reactance between these electrodes decreases in proportion to the increase in frequency. At the same time however, the inductive reactance of the coil 43 will also increase so that a higher potential will be impressed upon the grid 23 through the conductor 41. In practice it has been found that the feed-back energy may not increase as the linear function of the frequency, but may increase at a disproportionate rate. With this invention it is possible to neutralize such feed-back energy by constructing the coil 43 so that its inductive reactance will also vary at a disproportionate rate with the frequency. This 105 110 115 120 125 130

may be accomplished by introducing a small amount of distributive capacity between the windings of the coil 43 so that the reactance curve for the coils 43 and 40 taken together will not be a straight line. By adjusting the condenser 42 or by changing the coupling between the coils 40 and 43 the neutralizing potential may be varied for any one frequency.

I claim:

1. In a radio frequency system of the class described comprising an electron emission tube having input and output circuits each being associated with other circuits thru inductive coupling devices, said system having undesired feed-back of energy from the output circuit into the input circuit, and means including an inductance in series with a capacitance for impressing a neutralizing potential upon the input circuit to prevent local oscillations, said inductance being re-

moved from inductive relation to said coupling devices.

2. In a radio frequency system, an electron emission tube having the usual grid and plate electrodes connected to input and output circuits respectively, inductive coupling means in each circuit for associating the same with other circuits, and means including an inductance electrically connected 10 with the grid in series with a capacitance for impressing a neutralizing potential upon the input circuit to prevent local oscillations, said inductance being removed from inductive relation to said coupling means.
- 15 3. In a radio frequency system, an electron emission tube having the usual grid and plate electrodes connected to input and output circuits respectively, inductive coupling means in each circuit for associating the 20 same with other circuits, and means for impressing a neutralizing potential upon the input circuit to prevent local oscillations, said means including a transformer energized from the output circuit, one output terminal of the transformer being connected to the grid of the tube thru a capacitance, the transformer being removed from inductive relation to the coupling means.

4. In a radio frequency system, an electron emission tube having the usual grid and plate electrodes connected to input and output circuits respectively, inductive coupling means in each circuit for associating the same with other circuits, and means for 30 impressing a neutralizing potential upon the input circuit to prevent local oscillations, said means including a transformer having primary and secondary windings, the primary being energized by energy from the 35 output circuit, the secondary being connected to the input circuit in series with a capacitance, said windings being removed from inductive relation to said coupling means.

- 45 5. In a radio frequency system, an electron emission tube having the usual grid and plate electrodes connected to input and output circuits respectively and an electron emission element in common with said 50 circuits, a source of energy for the output circuit having its negative terminal connected to said emission element, an inductance having its one end connected to the positive terminal of said source and at its other end connected to said plate to place a positive 55 potential upon the same, a transformer for coupling said output circuit to another circuit, a capacitance in series with the input of said transformer, and another inductance 60 inductively coupled to said first inductance, said latter inductance having its one end electrically connected to said emission element and its other end connected to said grid in series with a capacitance, whereby 65 neutralization of undesirable feed-back en-

ergy is effected, said inductances being in substantially non-inductive relationship to said transformer.

6. In a radio frequency system, an electron emission tube having the usual grid and plate electrodes connected to input and output circuits respectively and an electron emission element in common with said circuits, a source of energy for the output circuit having its negative terminal connected 70 to said emission element, an inductance having its one end connected to the positive terminal of said source and at its other end connected to said plate to place a positive 75 potential upon the same, a transformer for 80 coupling said output circuit to another circuit, a capacitance in series with the input of said transformer, and means for causing the field of said inductance to induce a neutralizing potential upon said grid to prevent local oscillations due to feed-back energy, said inductance being in substantially 85 non-inductive relationship to said transformer.

7. In a radio frequency system, an electron emission tube having the usual grid and plate electrodes connected to input and output circuits respectively and an electron emission element in common with said circuits, means for inductively coupling said 90 input circuit to a source of high frequency energy, a source of energy for the output circuit having its negative terminal connected to said emission element, an inductance having 95 its one end connected to the positive terminal of said source and its other end connected to said plate to place a positive potential upon the same, a transformer for 100 coupling the output circuit to another circuit and connected to the output circuit in series 105 with a capacitance, said inductance being removed from inductive relation with both said coupling means and said transformer, and means for causing the field of said inductance to induce a neutralizing potential 110 upon said grid to prevent local oscillations due to feeding back of energy from the output circuit into the input circuit.

8. In a radio frequency system, an electron emission tube having the usual grid and plate electrodes connected to input and output circuits respectively and an electron emission element in common with said circuits, means for inductively coupling said input circuit to a source of high frequency energy, a source of energy for the output circuit having its negative terminal connected to said emission element, an inductance having its one end connected to the positive terminal of said source and its other end connected to said plate to place a positive potential upon the same, a transformer for 115 coupling the output circuit to another circuit and connected to the output circuit in series 120 with a capacitance, said inductance being removed from inductive relation with both said coupling means and said transformer, and means for causing the field of said inductance to induce a neutralizing potential 125 upon said grid to prevent local oscillations due to feeding back of energy from the output circuit into the input circuit.

tance being removed from inductive relation with both said coupling means and said transformer, and another inductance inductively coupled to said first inductance, said 5 latter inductance having its one end electrically connected to said emission element and its other end connected to said grid in series with a capacitance, thereby effecting neutralization of energy fed back from said 10 output circuit into said input circuit.

9. The method of effecting neutralization of undesirable feed-back energy in a radio frequency system characterized by the use of an electron emission tube having its in-

put and output circuits inductively coupled with other circuits, said method comprising resolving a portion of the energy in the output circuit into a magnetic field which is independent of the fields produced by said inductive coupling, causing this field to induce a potential, and impressing this potential upon the input circuit to neutralize the effect of feed-back energy from the output circuit into the input circuit. 15 20

In testimony whereof, I have hereunto set 25 my hand.

ROGER M. WISE.
